OXHYDROGEN-GAS JET.

1,097,284.

Specification of Letters Patent. Patented May 19, 1914.

Application filed October 8, 1908. Serial No. 456,694.

To all whom it may concern:

Be it known that I, EMMANUEL AUMONT, a citizen of the Republic of France, and resident of 43 Rue St. Lazare, Paris, France, 5 have invented an Oxyhydrogen-Gas Jet, of which the following is a description.

This invention relates to blowpipes working with a liquid fuel and particularly to blowpipes used for cutting and welding 10 metals.

The blowpipes hitherto employed generally utilize oxygen together with gaseous combustibles such as illuminating gas, acetylene, hydrogen, and the like. If these combustible gases are under pressure, they will 15 readily mix with the oxygen which is also under pressure; if, on the other hand, these combustible gases are not under pressure, it is necessary to entrain them by the flow of 20 the oxygen supplied through the agency of a device known as the Giffard injector and ordinarily employed in blowpipes for welding; in the case of liquid combustibles, however, if the method of entrainment referred 25 to above is employed, the following difficulty is encountered. In order to gasify the liquid after its entrainment, it must be heated by means of a flame. Now, this heating necessarily communicates heat to the 30 several parts of the injector and thus partially gasifies the liquid combustible before it enters the injector itself, which entirely 35 disturbs the quantity of the combustible flowing through the apparatus; in addition to this the heat supplied by conduction expands the various parts of the injector and thereby produces a variation in the dimensions of the parts which also disturbs the 40 regulation of the apparatus. The heating, is however, absolutely necessary in order to 45 gasify the liquid combustible and produce an intimate mixing of the combustible mixture; the heating also presents the advantage of raising the combustion temperature of the mixture.

In accordance with the present invention a special arrangement of the Giffard injector is employed, and it is isolated from the hot parts of the apparatus.

50 The accompanying drawing illustrates one mode of carrying the present invention into practice.

Instead of the device generally adopted in blowpipes, where the gas is supplied un-

der pressure through a central nozzle and 55 carries along in a restricted tube the gas at atmospheric pressure, the liquid combustible is supplied by a tube *a* through the central nozzle *A* and the oxygen under pressure through the annular passage *B*. Petroleum spirit for example may be used as the liquid combustible. Now the oxygen compressed at a high pressure (for instance, in the usual cylinders) first expands in the reducing valve of the cylinder and reaches 60 the injector through the regulating screw valve *V* on the blowpipe, which valve is arranged at the inlet to the injector and may also serve as a pressure reducer. The reduction in pressure is necessary in the case 65 of a cutting blowpipe (as is more convenient for hand blowpipes) in order to permit of the use of the same supply of oxygen for the cutting and the heating. The oxygen, after expanding through the screw valve as 70 *a*foresaid, passes around the injector in a very cold state, surrounds it with a gaseous envelop and so insulates it perfectly from the rest of the apparatus which may then be 75 heated as desired.

In order to obtain a still more complete calorific insulation between the injector and the tube *C* which is heated by a flame supplied for instance by a branch pipe *D*, it has been found advantageous to constitute 80 the whole or a portion of the part *E* of a metal which is a bad conductor of heat, such as German silver, nickel steel, or the like, or to interpose between the part *C* and the tube *E* a washer *W* of a substance which is 85 a bad conductor of heat.

By using the two means referred to above simultaneously the temperature of the injector can be kept constant so that the entrainment of the liquid combustible is constant also. This entrainment is regulated 90 at the beginning of the operation by means of the screw *K*, the extremity of which fills the outlet from the injector more or less completely.

The liquid combustible may either be sucked directly from an open vessel or be supplied from a vessel in which it is stored under pressure in any convenient manner; in the latter case, the injector will act as an 105 atomizer. Similar conditions of calorific insulation are required for the reason already stated in order to obtain an efficient

operation of the atomizer; the arrangement described above will enable them to be realized.

The arrangement described above for insulating the injector calorifically is applicable to all kinds of blowpipes for cutting or welding metal, the accompanying drawing being given by way of example only.

In particular it should be understood that the form of injector or atomizer described above for the entrainment of a liquid combustible is applicable not only to cutting blowpipes but to all blowpipes in which it is necessary to insulate an injector calorifically.

I claim:

1. A process of producing gaseous mixture of liquid fuel and oxygen in a blow pipe, said process consisting in feeding to the blow pipe the liquid fuel and cold compressed oxygen; mixing the oxygen with the fuel; and heating the resulting mixture in order to vaporize the fuel.

2. A process of producing gaseous mixture of liquid fuel and oxygen in a blow pipe, said process consisting in feeding to the blow pipe the liquid fuel and cold compressed oxygen; mixing the oxygen with the fuel; heating the resulting mixture in order to vaporize the fuel; and insulating the heat of said heating from the mixture during said mixing.

3. A process of producing gaseous mixtures of oxygen and liquid fuel in a blowpipe, said process consisting in causing compressed oxygen to partly expand whereby it becomes cold; circulating the cold oxygen in indirect contact with the liquid fuel; mixing the oxygen with the liquid fuel; and heating the mixture of oxygen and liquid fuel in order to vaporize the liquid fuel.

4. A process of producing gaseous mixtures of oxygen and liquid fuel in a blowpipe, said process consisting in causing compressed oxygen to partly expand whereby it becomes cold; circulating the cold oxygen in indirect contact with the liquid fuel; mixing the oxygen with the liquid fuel; heating the mixture of oxygen and liquid fuel in order to vaporize the liquid fuel; and insulating the heat of said heating from the mixture during said mixing.

5. A method for producing gaseous mixtures of oxygen and liquid fuel in a blowpipe, said process consisting in causing compressed oxygen to partly expand whereby it becomes cold; conducting it around a tube through which liquid fuel passes; mixing the oxygen and the liquid fuel; forcing them into a second tube in which the fuel is vaporized; and burning part of the gaseous mixture of oxygen and fuel to heat the mixture of oxygen and liquid fuel thus effecting the above vaporization of the fuel.

6. A process of producing gaseous mix-

tures of oxygen and liquid fuel in a blowpipe, said process consisting in causing compressed oxygen to partly expand whereby it becomes cold; conducting it into a chamber; feeding the liquid fuel through a tube in the central part of the chamber; forcing the oxygen and the liquid fuel through an injector at one end of said chamber and tube; passing the mixture of oxygen and liquid fuel to a second tube; heating the second tube; and burning part of the gaseous mixture of oxygen and fuel to heat the mixture of oxygen and liquid fuel, thus effecting the vaporization of the fuel.

7. A process of producing gaseous mixtures of oxygen and liquid fuel in a blowpipe, said process consisting in causing compressed oxygen to partly expand, whereby it becomes cold; conducting it into a chamber; feeding the liquid fuel through a tube in the central part of the chamber; forcing the oxygen and the liquid fuel through an injector at one end of said chamber and tube; regulating the flow of liquid fuel through the injector; passing the mixture of oxygen and liquid fuel to a second tube; heating the second tube; and burning part of the gaseous mixture of oxygen and fuel to heat the mixture of oxygen and liquid fuel thus effecting the above vaporization of the fuel.

8. In a gas jet apparatus, the combination of a body portion having therein an axial passage open at one end and having a lateral bore near the rear part thereof; a vaporizing tube secured to said body at its open end; a conducting tube in said passage and having a reduced forward end, said tube being spaced from the body portion; a needle screw in said conducting tube and forming therewith a thin cylindrical space extending to said reduced end; and means for conducting oxygen under pressure to said bore to permit the oxygen to expand around said tube in indirect contact with the fuel in said thin cylindrical space.

9. In a gas jet apparatus, the combination of a body portion having therein an axial passage open at one end and having a lateral bore near the rear part thereof; a vaporizing tube secured to said body at its open end; a conducting tube in said passage and having a reduced forward end, said tube being spaced from the body portion; a needle screw in said conducting tube and forming therewith a thin cylindrical space extending to said reduced end; means for conducting oxygen under pressure to said bore to permit the oxygen to expand around said tube in indirect contact with the fuel in said thin cylindrical space; and a valve in said last-named means.

10. In a gas jet apparatus, the combination of a body portion having therein an axial passage open at one end and having

a lateral bore near the rear part thereof, the diameter of said bore at its outlet end being less than one tenth of its principal diameter; a vaporizing tube secured to said body at its open end; a conducting tube in said passage and having a reduced forward end, said tube being spaced from the body portion; a needle screw in said conducting tube and forming therewith a thin cylindrical space extending to said reduced end; and means for conducting oxygen under pres-

sure to said bore to permit the oxygen to expand around said tube in indirect contact with the fuel in said thin cylindrical space.
